SWAN M. AKEYSON, OF LONG BEACH, CALIFORNIA

DISK BIT AND REAMER

Application filed April 28, 1930. Serial No. 447,787.

This invention relates to a disk bit and reamer, particularly useful for the drilling of oil wells by the rotary process.

The prime object of my invention is to provide a novel means whereby the cutting disks are positively rotated, while the entire bit is being rotated by the drill pipe.

Another object is to provide a bit of the character stated in which the reaming cutters act to rotate the disks as well as to ream the hole.

Still another object is to provide a novel bit of the character stated which will run smoother while operating in the hole, and which will, therefore, cut faster and with less wear on the machinery than bits heretofore in use.

Other objects, advantages, and features of invention may appear from the accompanying drawing, the subjoined detailed description, and the appended claims.

In the drawing

Figure 1 is a side elevation of my disk bit and reamer.

Figure 2 is a fragmentary view, partly in section and partly in elevation, of the lower part of the bit.

Figure 3 is a diagrammatic plan view of the cutters.

Figure 4 is a fragmentary view partly in section, of a slightly modified form of bit.

Referring more particularly to the drawing, the numeral 1 indicates a shank on the upper end of which a threaded coupling

pin 2 is provided so that the bit may be coupled to the drill pipe. A pair of spaced legs 3 and 4 depend from the shank 1 and the cutter members are journaled adjacent the lower end of the legs.

Disk cutters 5 and 6 are mounted on the inside of the legs 3, 4 respectively. Concentric with the disks 5 and 6, and positioned on the outside of the legs 3, 4 are two reaming cutters 7 and 8. These reaming cutters are preferably of the frusto-conical type, having teeth on the outer surface thereof. The disk and reaming cutter 5, 7 and 6, 8 are secured together and rotate in unison as will be further described.

The disks and reamers are journaled in

split sleeves 9 and 10, said sleeves being secured in the legs 3, 4 respectively. The inner end of each of the reamers is threaded as at 11, and this threaded portion screws into the hub portion of a cutter disk. Bolts 12 and 13 are countersunk in the reamers 8, 7 respectively and extends through the reamer and disk cutter. Nuts 14, 14' are countersunk flush with the inner surface of the disk and screw on to the bolt 12, 13 respectively, thus securely coupling the disk and the reamer together, and causes them to rotate in unison.

The legs 3, 4 are not in exact transverse alignment, but are set slightly ahead in the direction of rotation of the bit. Thus the leading portion only, of the reaming cutters 7, 8 will engage the side walls of the hole to ream said wall which causes the reaming cutter to rotate and will also positively rotate the disks 5, 6.

In Figure 4, I have disclosed a means whereby the bit may also overream as it advances in the hole. The only difference between the construction previously described, is that the disks and reaming cutters are permitted a small amount of lateral movement through the legs 3, 4. The hub portions of the disks 5, 6 are made slightly longer, or the inner end of the reaming cutters are slightly elongated, thus providing a shank as shown at 15, which permits the reaming cutters to move outwardly to ream the hole when the disks 5, 6 are on bottom and are digging.

Having described my invention, I claim:

1. A disk bit and reamer comprising a shank, a pair of spaced legs depending from the shank, a disk cutter journaled on the inside of each of the legs, a reaming cutter on the outside of the legs said reaming cutter being of lesser diameter than said disk, said reaming cutter being secured to the disk whereby the disk and reaming cutter will rotate together.

2. A disk bit and reamer comprising a shank, a pair of spaced legs depending from the shank, a disk cutter on the inside of each of the legs and journaled therein, a reaming cutter on the outside of each of the legs, said reaming cutter being of lesser diameter than

said disk, said reaming cutter being in axial alignment with the disk and secured thereto whereby the disks and reaming cutters will rotate together.

- 5 3. A disk bit and reamer comprising a shank, a pair of spaced legs depending from the shank, a disk journaled on the inside of each of the legs, a reaming cutter on the outside of each of the legs, said reaming cutter 10 being of lesser diameter than said disk, the inner end of said reaming cutters being threaded to screw into the disks, and a bolt extending through the reaming cutter and through the disk.
- 15 4. A disk bit and reamer comprising a shank, a pair of spaced legs depending from the shank, a disk rotatably mounted on the inside of each of said legs, a frusto-conical reaming cutter on the outside of each of the 20 legs, teeth on the outer surface of said cutters, means securing each of said reaming cutters to a disk whereby said disks and reaming cutters are rotatable in unison, and said cutters being of lesser diameter than said disks.

25 In testimony whereof, I affix my signature.
SWAN M. AKEYSON.
